UNITED STATES PATENT OFFICE.

WILLIAM C. WOODLAND, OF WARREN, OHIO, ASSIGNOR TO PACKARD ELECTRIC COMPANY, OF WARREN, OHIO, A CORPORATION OF OHIO.

WIRELESS TELEGRAPHY.

1,114,840.

Specification of Letters Patent.

Patented Oct. 27, 1914.

Application filed October 24, 1912. Serial No. 727,598.

To all whom it may concern:

Be it known that I, WILLIAM C. WOODLAND, of Warren, in the county of Trumbull and State of Ohio, have invented certain new and useful Improvements in Wireless Telegraphy; and I do hereby declare the following to be a full, clear, and exact description of the invention, such as will enable others skilled in the art to which it applies to make and use the same.

The primary object of this invention is to increase the group frequency or pitch of the tone heard at the receiving station of a wireless-telegraph system. This I accomplish by a high-group frequency, which is obtained by dividing up a multi-phase alternating current into a plurality of intermediate phases and taking off the current from each phase successively by a rotary element, the oscillating circuit of each phase being opened before the next one becomes active. All the phases are made use of for each signal and each phase is tuned alike. The discharges being equal in intensity and following each other at regular intervals will produce a smooth tone easily distinguishable through atmospheric disturbances.

In the accompanying drawings, Figure 1 is a diagrammatic view of the apparatus. Fig. 2 shows diagrammatically a wave representing single phase current. Fig. 3 represents the multiphase currents utilized by my invention.

In the art of wireless telegraphy it has heretofore been common to produce the electrical oscillations by discharging a condenser through a spark gap and a portion of a helix connected directly or indirectly to an aerial, the condenser being charged by exciting a transformer connected thereto upon closing the transmission key. Twice each cycle the condenser discharges through the spark gap and helix creating a high-frequency current, as is well known. The wave length of the high-frequency currents radiated by the aerial depends upon the value of the helix and condenser, but their pitch as received at the receiving station depends on the group frequency, and this in turn depends upon the frequency of the source of electrical supply. If this is 60 cycles there will be 120 groups per second, and this corresponds to a musical note too low to be read easily.

Heretofore it has been sought to break up

the group frequency in an effort to get more than one discharge for each one half cycle of current supply, but even if more than one discharge is produced such discharges manifestly cannot be equal in intensity. But according to my invention this difficulty is overcome, and a resultant high group frequency, producing a smooth note, is obtained. For this purpose I use a multi-phase alternating current which is tapped to give me the number of phases I desire, preferably six. With the latter I obtain a group frequency of 720 per second when excited with three-phase 60 cycle current. The circuit of each phase comprises a separate transformer, condenser, and spark terminal. A rotary element is designed to rotate in proximity to the separate sparking terminals, and if rotated in synchronism with the alternating current, each phase will discharge when the rotating sparking element comes opposite its respective sparking point, and such rotary element should be arranged to reach this point at the instant the condenser attains its maximum potential. The discharges from all the phases are therefore picked up by the rotary element and carried through the helix and back to a point connecting all the condensers and transformers. The sending key must necessarily be arranged to operate two circuits at once.

My invention will be readily understood from the drawings, wherein—

1 is a multi-phase transformer from which is tapped a series of phases, preferably six in number, although the number may be increased or lessened. The multiphase current may be supplied direct from an alternating current generator having the necessary number of phases, but I prefer to use the transformer. The circuit of each phase embodies a transformer 2; a condenser 3, and a spark-gap terminal 4, the terminals for the several phases being shown as arranged on an arc of a circle in proximity to a rotating element 5 which is designed to successively come into position to allow a spark to pass between itself and each terminal. This rotary element is connected to a helix 6, which in turn is directly or inductively connected to an aerial 7, and, in addition to a ground connection, the helix has a return connection with the transformers of the several intermediate phases. A double key 8 must be capable of operating

two circuits of the main at once when a three phase source is used.

The present invention may be more clearly understood by reference to the diagrammatic Figs. 2 and 3. The former shows the standard representation of an ordinary 60 cycle wave. From the point *a* to *c* is one whole wave or cycle, and from *a* to *b* is a half wave, the distance being $1/120$ of a second. Sparks will be produced in the spark gap at approximately the crests of the waves indicated at *s*. As shown in Fig. 3 in addition to the wave *a b c* I introduce additional waves, and when the positive and negative halves of these waves are considered alike, the crests of the waves follow each other at equal intervals, and altogether there are six times as many as there are in a pure 60 cycle current. Of course, any number of intermediate waves are readily obtainable from a multi-phase current. I use either a three-phase or a two-phase transformer excited by a suitable dynamo as the source of supply. With a six-phase arrangement I obtain a group frequency of 720 per second when excited with a three phase 60 cycle current. The tone produced about corresponds to the note high F of the musical scale.

The advantages of my invention will be readily appreciated. A high group frequency is obtained without the use of an expensive high frequency dynamo; a large number of corresponding small transformers being used, if one of them burns out it may be easily replaced without much expense, and such burning out does not cripple the entire station. This is also true of the condensers. It will also be noted that according to my invention I obtain a number of low frequency electric discharges forming a series of discharges of higher frequency, and that by the use of the rotary element for producing the successive discharges each phase is opened before the next one becomes active, and each discharge will

be equal in intensity and produce an easily distinguishable smooth tone. The use of stationary spark gaps would not accomplish this result satisfactorily, because of the indefiniteness of the point of maximum potential, and because, especially when the number of phases is large and the logarithmic decrement low, the discharges of two or more phases are likely to take place concurrently. By means of the rotary sparking element all danger of concurrent discharges is eliminated because the circuit of each phase is always open excepting at the time for its proper discharge. 60

I claim as my invention:

1. In a sender for wireless telegraphy, a multi-phase alternating current producer, and a plurality of energy-consuming devices energized by said producer in a multi-phase relation to each other, and comprising each a transformer, a condenser, and a sparking terminal, in combination with a helix common to all said devices, and a rotary element coöperating with said sparking terminals for effecting the successive discharge of said condensers through the helix. 65

2. In a sender for wireless telegraphy, a multi-phase alternating current producer, and a plurality of energy-consuming devices energized by said producer in multi-phase relation to each other, and comprising each a transformer, a condenser, and a sparking terminal, in combination with a helix common to all said devices, and a rotary element coöperating with said sparking terminals to effect the successive discharge of each condenser through the helix at the instant of its maximum potential. 70

In testimony whereof, I have signed this specification in the presence of two subscribing witnesses.

WILLIAM C. WOODLAND.
